UNITED STATES PATENT OFFICE

129,945

DESIGN FOR A HEATING STOVE

Karl W. Rausch, Cleveland Heights, Ohio, assignor to Perfection Stove Company, Cleveland, Ohio, a corporation of Ohio

Application August 7, 1941, Serial No. 102,718

Term of patent 14 years

To all whom it may concern:

Be it known that I, Karl W. Rausch, a citizen of the United States, residing at Cleveland Heights, in the county of Cuyahoga and State of Ohio, have invented a new, original and ornamental Design for a Heating Stove, of which the following is a specification, reference being had to the accompanying drawing forming part hereof, and wherein Fig. 1 is a front elevation, Fig. 2 a side elevation, and Fig. 3 a plan view of a heating stove showing my new design. The

side of the heating stove opposite that shown in Fig. 2 is the same as the latter, and each side panel is characterized by a conventional grille area, the one appearing in Fig. 2 being indicated at top and bottom and its limits otherwise defined by the dot-and-dash lines.

I claim:

The ornamental design for a heating stove, as shown and described.

KARL W. RAUSCH,
